UNITED STATES PATENT OFFICE.

JEFFREY T. FERRES, OF ANDERSON, INDIANA, ASSIGNOR TO J. W. SEFTON MANUFACTURING COMPANY, OF ANDERSON, INDIANA, AND CHICAGO, ILLINOIS, A CORPORATION OF INDIANA.

SHIPPING-PACKAGE.

SPECIFICATION forming part of Letters Patent No. 697,463, dated April 15, 1902.

Application filed August 12, 1901. Serial No. 71,791. (No model.)

To all whom it may concern:

Be it known that I, JEFFREY T. FERRES, a citizen of the United States, residing at Anderson, in the county of Madison, in the State 5 of Indiana, have invented a certain new and useful Improvement in Shipping-Packages, of which the following is a description, reference being had to the accompanying drawings, forming part of this specification.

10 My invention has for its object the provision of a light and cheap shipping-package to be used as a substitute for wooden boxes where the merchandise to be shipped is not of a heavy nature and does not require a particu- 15 larly strong and heavy box.

My improved package consists of a wooden crate of suitable construction and a separate lining of heavy corrugated paper. This lining is formed of a convenient number of 20 pieces, preferably four, and constitutes the four sides and top and bottom of the package within the wooden crate. The several parts making up this lining are adapted to be shipped and stored in flat form independ- 25 ently of the wooden crate and to be applied to the crates as a lining therefor when the crates are ready for use. The linings can be manufactured and supplied by the manufacturers of corrugated paper and shipped to 30 their customers in very compact form, while the latter can store them in the same form until required for use, when they can be applied as needed to crates either made up by such parties or obtained by them from any 35 near and convenient source of supply.

In the accompanying drawings, Figure 1 is a perspective view of one of the complete packages, composed of the exterior wooden crate and the interior corrugated paper lining, with the top of the crate removed and showing the top or lid of the lining in closed position; Fig. 2, a corresponding perspective view of the lining in assembled condition, but removed from the crate, and with 40 the top or lid of the lining in open position and the near end piece of the lining removed to expose the interior of the package; Fig. 3, a corresponding perspective view looking at the rear right-hand corner (instead of the forward 45 right-hand corner) of the package, with the

lining-piece constituting the rear side and top or lid of the lining, as well as the near end piece, removed to better expose the lining-piece constituting the bottom and forward wall of the lining; Fig. 4, a vertical 55 cross-section of the complete shipping-package looking at the inner surface of the left-hand end thereof; Figs. 5, 6, and 7, views corresponding to Figs. 2, 3, and 4, but showing a modified construction of the lining; and Fig. 60 8, a perspective view of one of the end pieces of such modified construction.

The same letters of reference are used to indicate identical parts in the several views.

The wooden crate A may be built up in the usual or any suitable manner, in the present instance being composed of the rectangular end frames a, having the vertical slats b nailed to their inner surfaces, the opposite ends of the side slats c nailed to their outer edges, the top slats c', Fig. 4, to their upper edges, and the bottom slats d to their lower edges. The end pieces of the lining, under the construction illustrated in Figs. 1 to 3, consist of plain flat boards B, of double-faced 70 corrugated paper, and fit snugly against the opposite ends of the crate A. In assembling the several parts of the lining within the crate these end pieces are preferably and most conveniently inserted first. The top and bottom and two opposite sides of the lining are, under the construction illustrated in Figs. 1 to 3, composed of two separate pieces, which are substantial duplicates of each other, one piece constituting the top C and one side D 75 of the lining, and the other piece constituting the bottom E and the opposite side F thereof, said sides being hinged to said top and bottom, respectively, by suitable scores or creases. The top and bottom and oppo- 80 site sides of these lining-pieces are provided with narrow end flanges e, while each of the sides is provided at its free edge with a like longitudinal flange f. These flanges are adapted to be bent at right angles to the lining-pieces and serve to lock the several parts of the lining in position within the crate and prevent them being collapsed or pressed inward. The end flanges e of course hold the end pieces B B of the lining in place against 95 100

the opposite ends of the crate, as will be readily understood. The flange *f* at the bottom of the side *D* rests upon the free edge of the bottom *E* of the lining and holds it down, as 5 will be also understood from Fig. 2. In addition to this the end flanges *e* of the side, top, and bottom are cut away at right angles to each other at their adjacent ends, so that when the top, bottom, and sides of the lining 10 are placed in position in the crate the adjacent ends of these end flanges will abut squarely against each other and serve to lock the top, bottom, and sides against inward movement. Thus in Fig. 2 it will be seen that the bottom 15 of the vertical end flanges *e* at the opposite ends of the side *D* abut squarely against the rear ends of the flanges *e* at the opposite ends of the bottom *E* at *x x*, so that the rear edge of the bottom *E* is locked down by the end 20 flanges *e* of the side *D*, (as well as by the bottom flange *f* of said side,) while the side *D* is itself locked from inward movement by the flanges *e* of the bottom *E*. Likewise, as seen in Fig. 3, the lower ends of the vertical flanges 25 *e* at the opposite ends of the side *F* abut against the forward ends of the flanges *e* of the bottom *E* at *y y*, and thereby lock the side *F* from inward movement. In addition to this when the top *C* is swung downward to 30 horizontal position the opposite ends of the end flanges *e* of said top will abut against the upper ends of the vertical end flanges *e* of the opposite sides of the box, as seen at *z* in Fig. 4, so that when the top of the crate is then 35 nailed in place the entire lining will be locked in position against the inside walls of the crate and be prevented from collapsing under shocks and jars or extraneous pressure through the openings in the crate.

- 40 The longitudinal flange *f* along the upper edge of the front wall *F* of the box is bent downward to horizontal position before the top *C* is closed and serves to support the forward edge of the latter and close the joint, 45 which would otherwise be left more or less open between the upper edge of the wall *F* and forward edge of said top. Inasmuch, however, as the forward side of the top *C* is supported at its opposite ends by the abut- 50 ment of the front ends of its end flanges *e* with the upper ends of the end flanges *e* of the front wall *F*, Fig. 4, the flange *f* is not so essential as the end flanges *e*, and the same is true of the flange *f* along the lower edge 55 of the side wall *D*. Nevertheless, both of these flanges add to the finish and perfection of the lining and it is advantageous to employ them.

- 60 In Figs. 5, 6, 7, and 8 I have illustrated a modified construction of lining in which the locking-flanges *e* are formed upon the end walls *B B* of the lining instead of being formed upon the top and side walls. Under this construction each of the end pieces *B B* 65 is provided upon all four of its edges with flanges *e*, Fig. 8, while the front and rear side walls of the box are provided at their upper

and lower edges, respectively, with flanges *f*, Figs. 5 and 6, as in the other construction. In assembling the parts of the lining the end 70 pieces *B B* are first inserted in position at the opposite ends of the crate, with their bottom and side flanges *e* bent at right angles and resting against the bottom and front and rear walls of the crate, the top flanges *e* of said 75 end pieces being left in vertical position. The lining-piece comprising the bottom *E* and front wall *F* of the lining is then inserted, the bottom *E* resting at its opposite ends upon the bottom flanges *e* of the end pieces *B B*, 80 while the front wall *F* fits at its opposite ends against the front end flanges *e* of the end pieces *B B*, Figs. 5 and 7. The lining-piece comprising the rear wall *D* and top *C* is then inserted, the flange *f* along the bottom of said 85 rear wall resting upon the otherwise free rear edge of the bottom *E* and serving to lock it down, Fig. 5. The rear wall *D* fits at its opposite ends against the vertical flanges *e* of the end pieces *B B*, Fig. 7. Before the top 90 or lid *C* is now swung downward to closed position the flanges *e* at the upper ends of the end pieces *B B* are bent down to horizontal position between the front and rear walls of the lining, and thereby serving to firmly lock 95 those parts of the lining in position against the front and rear walls of the crate. The flange *f* along the upper edge of the front wall *F* is then bent down to horizontal position upon the front ends of the flanges *e* of the 100 end pieces *B B*, Figs. 5 and 6, and the top *C* then swung downward to closed position, resting at its side edges upon said flanges *e* of the end pieces and at its forward edge upon said flange *f* of the front wall, Fig. 7. This 105 construction furnishes a finished and tightly-closed lining, all the parts of which are locked in position excepting the lower edge of the rear wall *D*, which latter is left subject to inward movement from the exterior pressure, and in this respect the lining is less desirable than the construction first described.

By either of the constructions above described I provide a shipping-package which will not only serve the purpose of a heavy 115 wooden box in shipping a great variety of merchandise, but a package which is much less expensive in the first instance than a wooden box and which may be more conveniently handled and be shipped at less expense 120 than such box. Moreover, when the topslats of the crate have been removed after a shipment of merchandise in my improved package a complete closed package provided with a hinged lid remains, which may be employed 125 for any of the convenient purposes of a box with a hinged lid or in which the merchandise shipped may be left and still be protected from dust and dirt until gradually withdrawn for use or sale.

Having thus fully described my invention, I claim—

1. A shipping-package comprising an outer wooden crate and an inner lining composed of

a series of four separate disconnectible interlocking paper boards forming the top and bottom and the end and side walls, substantially as described.

5 2. A shipping-package comprising an outer wooden crate and an inner lining composed of a series of separate interlocking corrugated paper boards, the top and bottom being connected respectively with the front and rear 10 side walls; substantially as described.

15 3. A shipping-package comprising an outer wooden crate and an inner lining of disconnectible corrugated paper boards provided with interlocking flanges operating to hold 20 the several boards of the lining in position; substantially as described.

25 4. A shipping-package comprising an outer crate and an inner lining formed of four separate pieces, two of said pieces constituting the 30 end walls of the lining, another the bottom and front wall thereof hinged together, and the fourth the top and rear wall likewise hinged together and permitting said top to be swung upward to open position and downward to closed position; substantially as described.

35 5. A shipping-package comprising an outer crate and an inner lining formed of four separate pieces, two of said pieces constituting the 40 end walls of the lining and the other two constituting, respectively, the bottom and front wall, and the top and rear wall, thereof, the rear wall being provided along its lower edge with an inturned locking-flange resting upon the rear edge of the bottom of the lining, and the front wall being provided upon its upper edge with an inturned flange to support the forward edge of the top of the lining in closed position; substantially as described.

45 6. A shipping-package comprising an outer crate and an inner lining formed of four separate pieces, two of said pieces constituting the end walls of the lining, and the other two constituting, respectively, the bottom and front 50 wall, and the top and rear wall, thereof, and certain of said pieces being provided with locking-flanges operating to hold the several parts of the lining in position and prevent inward movement thereof; substantially as described.

55 7. A shipping-package comprising an outer crate and an inner lining composed of the two end pieces B B, the bottom E with the vertical front wall F hinged thereto and provided at its upper edge with the flange f, and the rear wall D having the top C hinged to its upper edge and provided at its lower edge with the flange f resting upon the rear edge of the bottom E; substantially as described.

60 8. A shipping-package comprising an outer crate and an inner lining composed of the two plain end pieces B B, the bottom E provided with the end flanges e e and having hinged to its forward edge the front wall F provided 65 with like end flanges e e, the rear wall D provided with the end flanges e e and having hinged to its upper edge the top C provided

with like end flanges e e, said end flanges e being cut away at right angles to each other at their adjacent ends so that when the lining is assembled within the crate they will abut against each other and lock the top, bottom and sides of the lining against inward movement; substantially as described. 7c

9 9. A shipping-package comprising an outer 75 crate and an inner lining composed of the two plain end pieces B B, the bottom E provided with the end flanges e e and having hinged to its forward edge the front wall F provided with like end flanges e e and also with the flange f along its upper edge, and the rear wall D provided with the end flanges e e and bottom flange f and having hinged to its upper edge the top C provided with the end flanges e e and adapted to rest at its forward 85 edge, when in closed position, upon the flange f at the upper edge of the front wall F; substantially as described.

10 10. The herein-described crate-lining, composed of four separate pieces, two of said 90 pieces being duplicates of each other and constituting the end walls of the lining, and the other two pieces being also duplicates of each other and constituting, respectively, the bottom and front wall, and the top and rear wall, 95 of said lining, the top being hinged to the upper edge of the rear wall so as to swing upward to open position or downward to closed position; substantially as described. 10c

11 11. The herein-described crate-lining composed of four separate pieces, two of said 105 pieces being duplicates of each other and constituting the end walls of the lining, and the other two being also duplicates of each other and constituting, respectively, the bottom 110 and front wall of the lining with a longitudinal flange projecting from the upper edge of the front wall, and the rear wall and top of the lining with a longitudinal flange projecting from the bottom of the rear wall, the top 115 wall being hinged to the upper edge of the rear wall so as to swing upward to open position or downward to closed position; substantially as described.

12 12. The herein-described crate-lining composed of four separate pieces, two of said 120 pieces being plain flat boards constituting the end walls of the lining and the other two of said pieces being duplicates of each other and constituting, respectively, the bottom and front wall of the lining, each provided with end flanges, and the top and rear wall of the lining, each also provided with end flanges, said end flanges being cut away at right angles to each other at their adjacent ends so 125 as to abut together when the lining is assembled within the crate and lock the top, bottom and sides of the lining from inward movement; substantially as described. 125

13 13. The herein-described crate-lining composed of four separate pieces, two of said 130 pieces being plain flat boards constituting the end walls of the lining, and the other two pieces being duplicates of each other and constitut-

ing, respectively, the bottom and front wall of the lining, each provided at its upper ends with locking-flanges and the front wall provided at its upper edge with a longitudinal flange, and the rear wall and top of the lining, each provided with end flanges and said rear wall provided at its lower edge with a longitudinal flange adapted to rest upon the rear edge of the bottom of the lining, said end flanges of the top, bottom and sides being cut away at right angles to each other so as to abut together when the lining is assembled within the crate and lock said parts from inward movement; substantially as described.

14. A shipping-package comprising an outer crate and an inner lining formed of two separate end pieces and two substantially similar pieces of two parts each hinged together, one of which pieces forms the bottom and one side wall and the other of which forms the opposite side wall and the top; substantially as described.

15. The herein-described crate-lining composed of four separate pieces, two of said pieces being duplicates of each other and constituting the end walls of the lining and the other two of said pieces also being duplicates of each other and constituting respec-

tively the bottom and one side wall and the top and the other side wall; substantially as described.

16. The herein-described crate-lining composed of four separate pieces adapted to interlock and thereby form a supported unitary structure within the crate, two of said pieces being duplicates of each other and constituting the end walls of the lining and the other two of said pieces also being duplicates of each other and constituting respectively the bottom and one side wall and the top and the other side wall; substantially as described.

17. The herein-described crate-lining composed of four separate pieces two of said pieces being duplicates of each other and constituting the end walls of the lining and the other two of said pieces also being duplicates of each other and constituting respectively the bottom and one side wall and the top and the other side wall, said latter two pieces having flanges beveled at their ends to abut against each other when the lining is in position; substantially as described.
